FIG. 1

FIG. 2

FIG. 3

FIG. 4

FIG.5

FIG. 6

1
HERMETIC COMPRESSOR

CROSS REFERENCE TO PRIOR APPLICATION

This application is a National Stage Patent Application of PCT International Patent Application No. PCT/JP2022/015379 (filed on Mar. 29, 2022) under 35 U.S.C. § 371, which claims priority to Japanese Patent Application No. 2021-153196 (filed on Sep. 21, 2021), which are all hereby incorporated by reference in their entirety.

FIELD

The present invention relates to a hermetic type compressor that compresses and conveys a refrigerant in a refrigeration machine or an air conditioner operated by using a refrigeration cycle.

BACKGROUND

There is a known compressor, as a hermetic type compressor, that is constituted to have a structure in which a compression section and a motor, which drives the compression section, are accommodated in an interior portion of a compressor main body container having a vertical cylindrical shape, and an accumulator container, which is used to separate a refrigerant into a gas refrigerant and a liquid refrigerant (hereinafter, sometimes referred to as “to separate a gas-liquid two-phase refrigerant”) and which causes only the gas refrigerant to be sucked into a compression section, is provided at a lower part of the compressor main body container.

The compressor described in Patent Literature 1 is a compressor having a compression section with a rotary type. This compressor has a structure in which an accumulator container that separates a gas-liquid two-phase refrigerant, which is sucked into the compression section, is constituted by a container, which is formed independently of a compressor main body container, and that is arranged below the compressor main body container, and the compressor main body container is connected to the accumulator container by using a bracket.

The compressor described in Patent Literature 2 is a compressor having a compression section with a scroll type. This compressor has a structure in which an accumulator container is directly bonded to a lower part of a compressor main body container, which accommodates a compression section and a motor that drives the compression section.

The compressor described in Patent Literature 3 has a structure, in which an interior portion of an airtight container is divided by a pressure partition wall, an upper part of the pressure partition wall is used as a compressor main body container, in which a compression section and a motor are accommodated, and a lower part of the pressure partition wall is used as an accumulator container.

SUMMARY

Technical Problem

As described above related to Patent Literatures 1, 2, and 3, in the compressor in which the accumulator container is bonded to a bottom portion of the compressor main body container, in order to implement a highly reliable hermetic type compressor capable of reducing a manufacturing cost of the compressor and preventing a leakage of a refrigerant from the compressor main body container to the accumulator container, a structure, in which an upper end portion of the accumulator container is welded to the bottom portion of the compressor main body container, is conceived. However, if the accumulator container is bonded to the compressor main body container, heat, which is generated at the interior portion of the compressor main body container, is likely to be conducted to the accumulator container, the refrigerant, which is contained in the accumulator container, may possibly be heated. As a result of the refrigerant, contained in the accumulator container, is heated, the temperature of the refrigerant, sucked from the accumulator container to the compressor main body container, rises, and the compression efficiency of the rotary compressor is decreased due to an occurrence of a pressure loss produced in accordance with the temperature rise.

Accordingly, the disclosed technology has been conceived in light of the circumstances described above, and an object thereof is to provide a hermetic type compressor capable of enhancing the thermal insulation property between the accumulator container, which is bonded to the compressor main body container, and the compressor main body container.

Solution to Problem

According to an aspect of an embodiments in the present application, a hermetic type compressor includes: a compressor main body container that is a vertical type having a cylindrical shape, and that is provided with a discharge pipe and a suction pipe for a refrigerant; an accumulator container that is connected to the suction pipe; a compression section that is arranged inside the compressor main body container, that compresses the refrigerant, which has been sucked from the accumulator container by way of the suction pipe, and that discharges the compressed refrigerant from the discharge pipe; and a motor that is arranged inside the compressor main body container, and that drives the compression section, wherein the accumulator container includes an accumulator shell having a cup shape, and in which an opening side of the accumulator shell is bonded to the compressor main body container, a partition member, which partitions an interior portion of the accumulator shell, is provided in the interior portion, and a thermal insulation section, which includes an interior portion space having a hollow structure that blocks a heat transfer from the compressor main body container to the accumulator container, is formed between the partition member and a bottom shell that is included in the compressor main body container.

Advantageous Effects of Invention

According to an aspect of an embodiment of a hermetic type compressor disclosed in the present application, it is possible to enhance a thermal insulation property between

an accumulator container, which is bonded to a compressor main body container, and the compressor main body container.

BRIEF DESCRIPTION OF DRAWINGS

FIG. 1 is a longitudinal sectional diagram illustrating a rotary compressor according to an embodiment.

FIG. 2 is an exploded perspective diagram illustrating a compression section of the rotary compressor according to the embodiment.

FIG. 3 is a perspective diagram illustrating the rotary compressor according to the embodiment.

FIG. 4 is an enlarged longitudinal sectional view of a relevant part in a first modification.

FIG. 5 is an enlarged longitudinal sectional view of a relevant part in a second modification.

FIG. 6 is an enlarged longitudinal sectional view of a relevant part in a third modification.

DESCRIPTION OF EMBODIMENTS

Preferred embodiments of a hermetic type compressor disclosed in the present invention, will be described in detail below with reference to the accompanying drawings. Furthermore, the hermetic type compressor, disclosed in the present invention, is not limited by the embodiments described below.

Embodiment

Configuration of Rotary Compressor

In the present embodiment, a rotary compressor will be described as one example of the hermetic type compressor. FIG. 1 is a longitudinal sectional diagram illustrating a rotary compressor according to an embodiment. FIG. 2 is an exploded perspective diagram illustrating a compression section of the rotary compressor according to the embodiment.

As illustrated in FIG. 1, a rotary compressor 1 is a hermetic type compressor with an internal high pressure type that is constituted to have a structure, in which a compression section 12 that sucks a refrigerant from a compression section suction pipe 102, that compresses the sucked refrigerant, and that discharges the compressed refrigerant to the interior portion of a compressor main body container 10, and a motor 11 that drives the compression section 12, are accommodated in an interior portion of the compressor main body container 10, and a high pressure refrigerant, which has been compressed by the compression section 12, is discharged to the interior portion of the compressor main body container 10, and is further discharged to a refrigeration cycle through a discharge pipe 107.

The compressor main body container 10 includes a main shell 10a having a vertical cylindrical shape, a top shell 10b having a cup shape, and a bottom shell 10c having a cup shape, and is constituted to have a structure, in which an opening side 10g of the top shell 10b is secured to an upper end portion of the main shell 10a at a first weld portion V by performing a welding process, and an opening side 10d of the bottom shell 10c is secured to a lower end portion of the main shell 10a at a second weld portion W by performing a welding process.

The compression section suction pipe 102, which is used to suck a low pressure refrigerant in a refrigeration cycle into

the compression section 12, is provided by passing through the main shell 10a. Specifically, a guide tube 101 is secured to the main shell 10a by being subjected to brazing, and the compression section suction pipe 102 passes through an inner side of the guide tube 101, and is secured to the guide tube 101 by being subjected to brazing.

The discharge pipe 107, which is used to discharge a high pressure refrigerant that has been compressed by the compression section 12 from the interior portion of the compressor main body container 10 to the refrigeration cycle, is provided by passing through the top shell 10b. The discharge pipe 107 is directly secured to the top shell 10b by being subjected to brazing.

An accumulator container 25, which is used to suck, into the compression section 12, only a gas refrigerant obtained by separating a low pressure gas-liquid two-phase refrigerant that is sucked from the refrigeration cycle, is provided below the compressor main body container 10. Specifically, the accumulator container 25 is formed by securing an opening side 26a of an accumulator shell 26 to an opposite opening side 10e of the bottom shell 10c at a third weld portion X by performing a welding process and hermetically sealing the interior portion of the accumulator shell 26 at a position lower than the second weld portion W, in which the main shell 10a and the bottom shell 10c included in the compressor main body container 10 are welded.

In the accumulator shell 26, each of an accumulator suction pipe 27, which is used to suck a refrigerant into the interior portion of the accumulator container 25 from the refrigeration cycle, and a gas-liquid separation tube 31, which is used to convey a gas refrigerant from the interior portion of the accumulator, passes through the accumulator shell 26, and is secured to the accumulator shell 26 by being subjected to brazing.

The gas-liquid separation tube 31 is connected to the compression section suction pipe 102 on the outside of the accumulator container 25 via a suction pipe 104.

A base member 310, which supports the entirety of the rotary compressor 1, is welded and secured to the lower part of the accumulator shell 26.

The compression section 12 includes a cylinder 121, an upper end plate 160T, a lower end plate 160S, and a rotation shaft 15, and the upper end plate 160T, the cylinder 121, and the lower end plate 160S are laminated in this order, and are secured by a plurality of bolts 175. The upper end plate 160T is provided with a main bearing portion 161T. The lower end plate 160S is provided with a secondary bearing portion 161S. The rotation shaft 15 is provided with a main shaft portion 153, an eccentric portion 152, and a secondary shaft portion 151. The main shaft portion 153, provided in the rotation shaft 15, is fitted into the main bearing portion 161T, provided in the upper end plate 160T, and the secondary shaft portion 151, provided in the rotation shaft 15, is fitted into the secondary bearing portion 161S, provided in the lower end plate 160S, so that the rotation shaft 15 is rotatably supported.

The motor 11 includes a stator 111 that is arranged on an outer side, and a rotor 112 that is arranged on an inner side. The stator 111 is secured to the inner circumferential surface of the main shell 10a by using a shrink fit process. The rotor 112 is secured to the rotation shaft 15 by using a shrink fit process.

In the interior portion of the compressor main body container 10, in order to lubricate a sliding member of the compression section 12 and seal a high pressure section and a low pressure section, which are included in a compression

chamber, lubricating oil 18 with an amount, which is enough to substantially immerse the compression section 12, is enclosed.

In the following, the compression section 12 will be described in detail with reference to FIG. 2.

A hollow portion 130, which has a cylindrical shape, is provided in the interior portion of the cylinder 121, and a piston 125 is arranged at the hollow portion 130. The piston 125 is fitted into the eccentric portion 152, which is provided in the rotation shaft 15. The cylinder 121 is provided with a groove portion that is outwardly provided from the hollow portion 130, and a vane 127 is arranged at the groove portion. The cylinder 121 is provided with a spring hole 124 leading from the outer circumference to the groove portion, and a spring 126 is arranged in the spring hole 124. As a result of one end of the vane 127 being pressed against the piston 125 by the spring 126, an outer space of the piston 125 is divided into a suction chamber 133 and a discharge chamber 131 at the hollow portion 130 of the cylinder 121. The cylinder 121 is provided with a suction hole 135 that communicates from the outer circumference to the suction chamber 133. The compression section suction pipe 102 is connected to the suction hole 135. The upper end plate 160T is provided with a discharge hole 190, which passes through the upper end plate 160T and communicates with the discharge chamber 131. On the upper end plate 160T, a discharge valve 200, which opens and closes the discharge hole 190, and a discharge valve holder 201, which prevents warpage of the discharge valve 200, are secured by a rivet 202. On the upper side of the upper end plate 160T, an upper end plate cover 170, which covers the discharge hole 190, is arranged, so that an upper end plate cover chamber 180, which is blocked by the upper end plate 160T and the upper end plate cover 170, is formed. The upper end plate cover 170 is secured to the upper end plate 160T by the plurality of bolts 175 each of which secures the upper end plate 160T and the cylinder 121. The upper end plate cover 170 is provided with an upper end plate cover discharge hole 172, which communicates between the upper end plate cover chamber 180 and the interior portion of the compressor main body container 10.

In the following, a flow of a refrigerant, which is sucked in by a rotation of the rotation shaft 15, will be described.

The piston 125, which is fitted into the eccentric portion 152 provided in the rotation shaft 15, performs an orbital motion caused by a rotation of the rotation shaft 15, so that the suction chamber 133 sucks a refrigerant while increasing its volume. As a suction path of the refrigerant, a low pressure refrigerant in the refrigeration cycle is sucked into the interior portion of the accumulator container 25 by way of the accumulator suction pipe 27, and, in the case where a liquid is mixed with the refrigerant that has been sucked into the accumulator container 25, the refrigerant is retained in a lower part of the accumulator container 25, and only the gas refrigerant is sucked into the gas-liquid separation tube 31 that is upwardly opened in the interior portion of the accumulator container 25. The gas refrigerant, sucked into the gas-liquid separation tube 31, is sucked into the suction chamber 133, after passing through the suction pipe 104 and the compression section suction pipe 102. If a large amount of the liquid refrigerant is contained in the refrigerant that is to be sucked from the refrigeration cycle, the liquid level of the liquid refrigerant becomes higher than the position of an open end 31b of the gas-liquid separation tube 31 in the interior portion of the accumulator container 25, and the large amount of liquid refrigerant may possibly flow into the gas-liquid separation tube 31. If the large amount of liquid

refrigerant flows into the compression section 12 through the gas-liquid separation tube 31, this causes damage to the compression section 12. In order to prevent a large amount of liquid refrigerant from flowing into the gas-liquid separation tube 31, the gas-liquid separation tube 31 is provided with a liquid return hole 34, which is used to suck a liquid refrigerant into the gas-liquid separation tube 31 little by little.

In the following, a flow of a refrigerant, which is discharged by a rotation of the rotation shaft 15, will be described.

The piston 125, which is fitted into the eccentric portion 152 provided in the rotation shaft 15, performs an orbital motion caused by a rotation of the rotation shaft 15, so that the discharge chamber 131 compresses the refrigerant while contracting its volume, and, if a pressure of the compressed refrigerant is higher than a pressure of the upper end plate cover chamber 180, disposed on the outer side of the discharge valve 200, the discharge valve 200 is opened, and then, the refrigerant is discharged from the discharge chamber 131 to the upper end plate cover chamber 180. The refrigerant, discharged to the upper end plate cover chamber 180, is discharged into the compressor main body container 10 from the upper end plate cover discharge hole 172, which is provided in the upper end plate cover 170.

The refrigerant, which has been discharged into the compressor main body container 10, is guided to an upper part of the motor 11 after passing through a notch (not illustrated) that is provided around the outer circumference of the stator 111 and that communicates between an upper and lower portions of the motor 11, or passing through a gap with a winding portion of the stator 111 (not illustrated) or a gap 115 between the stator 111 and the rotor 112 (see FIG. 1), and is discharged to the refrigeration cycle from the discharge pipe 107, which is provided in the top shell 10b.

In the following, a flow of the lubricating oil 18 will be described.

The lubricating oil 18, which is enclosed in the lower part of the compressor main body container 10, is supplied to the compression section 12 after passing through the interior portion (not illustrated) of the rotation shaft 15 by a centrifugal force generated by the rotation shaft 15. The lubricating oil 18, supplied to the compression section 12, is mixed with the refrigerant, is turned into a mist state, and is drained into the interior portion of the compressor main body container 10 together with the refrigerant. The lubricating oil 18, which has been turned into a mist state and drained into the interior portion of the compressor main body container 10, is separated from the refrigerant by the centrifugal force of a rotational force generated by the motor 11, and returns to the lower part of the compressor main body container 10 again in the form of oil drops. However, some of the lubricating oil 18 is not separated, and is drained into the refrigeration cycle together with the refrigerant. The lubricating oil 18, which has been drained into the refrigeration cycle, returns to the accumulator container 25 after circulating the refrigeration cycle, is separated at the interior portion of the accumulator container 25, and is retained in the lower part inside the accumulator container 25. The lubricating oil 18, retained in the lower part inside the accumulator container 25, flows into the gas-liquid separation tube 31 little by little after passing through the liquid return hole 34 together with the liquid refrigerant, and is sucked into the suction chamber 133 together with the sucked refrigerant.

Characteristic Configuration of Rotary Compressor

In the following, a characteristic configuration of the rotary compressor 1 according to the embodiment, will be

described. The characteristic feature of the present embodiment is that, as illustrated in FIG. 1, a thermal insulation member **36** is provided in the interior portion of the accumulator container **25**.

Structure of Thermal Insulation Section

FIG. 3 is a perspective diagram illustrating the rotary compressor **1** according to the embodiment. As illustrated in FIG. 1 and FIG. 3, in the interior portion of the accumulator shell **26** included in the accumulator container **25**, a partition member **28**, which partitions the interior portion, is provided, and, a thermal insulation section **35**, which blocks a heat transfer between the compressor main body container **10** and the accumulator container **25**, is formed between the partition member **28** and the bottom shell **10c** of the compressor main body container **10**. The thermal insulation section **35** is provided at a position adjacent to the bottom shell **10c** of the compressor main body container **10**, and includes an interior portion space **35a** that is formed in a hollow structure and that blocks a heat transfer from the compressor main body container **10** to the accumulator container **25**. In other words, the interior portion space **35a**, which is formed in a hollow structure, is an insulation space. As a result of this, it is possible to suppress a refrigerant, contained in the accumulator container **25**, from being heated by heat, which is generated in the interior portion of the compressor main body container **10**.

As described above, the accumulator container **25** includes the third weld portion **X** in which the opening side **26a**, which corresponds to the upper end portion of the accumulator shell **26**, is bonded to the bottom shell **10c** of the compressor main body container **10**. A circumference wall **28a** of the partition member **28** is bent toward the upper part of the accumulator shell **26**. The bent outer circumference surface of the circumference wall **28a** of the partition member **28** is bonded to the inner circumferential surface of the accumulator shell **26** by the fourth weld portion **Y**. Furthermore, each of the third weld portion **X** and the fourth weld portion **Y**, disposed at the accumulator shell **26**, is formed along the circumferential direction of the accumulator shell **26**.

Therefore, introduction space, to which the refrigerant is introduced in the accumulator shell **26**, is hermetically sealed by the partition member **28**. Furthermore, the interior portion space **35a**, which is included in the thermal insulation section **35**, is formed by the opening side **26a** of the accumulator shell **26**, the bottom shell **10c** provided in the compressor main body container **10**, and the partition member **28**.

Furthermore, although not illustrated, in the accumulator shell **26**, a through hole, which connects the interior portion space **35a** to an outer side of the accumulator shell **26**, may be provided by passing through the accumulator shell **26**. In the accumulator shell **26**, for example, the through hole, which passes through the accumulator shell **26**, is provided at a position opposite the thermal insulation section **35**, so that it is possible to take outside air contained in the accumulator shell **26** into the interior portion space **35a** by way of the through hole, and it is thus possible to drain the air, contained in the interior portion space **35a**, through the through hole. As a result of this, even when the air, which is contained in the interior portion space **35a** included in the thermal insulation section **35**, is heated by heat transferred from the compressor main body container **10** to the thermal insulation section **35**, the interior portion space **35a** included in the thermal insulation section **35**, is ventilated by way of

the through hole, so that it is possible to suppress a decrease in the thermal insulation property exhibited by the thermal insulation section **35**. Therefore, it is possible to appropriately maintain the thermal insulation property exhibited by the thermal insulation section **35**. Furthermore, a plurality of through holes may be provided in the accumulator shell **26**. In this case, it is possible to smoothly drain air, which has been taken into the interior portion space **35a** from one of the through holes, to the other of the through holes. In addition, in the case where a through hole is provided in the accumulator shell **26**, coating for preventing rust being formed caused by dew condensation occurring in the interior portion space **35a**, is applied on the inner surface of the interior portion space **35a**.

Furthermore, in the case where the through hole (not illustrated) described above is provided in the accumulator shell **26**, for example, the through hole is provided at a position between the bottom shell **10c**, included in the compressor main body container **10**, and the partition member **28** in the vertical direction of the accumulator container **25**, but the position of the through hole is not limited. Although not illustrated, the through hole may be arranged at the lower part of the interior portion space **35a**, which is included in the thermal insulation section **35**, and may be arranged, for example, in the vicinity of the fourth weld portion **Y**, in which the partition member **28** is bonded to the inner circumferential surface of the accumulator shell **26**. As a result of this, for example, coating, which is applied on the inner surface of the interior portion space **35a** included in the thermal insulation section **35**, may be applied by, for example, electrodeposition coating. In a case of the electrodeposition coating, the accumulator container **25**, which is an object to be coated, is immersed in a tank in which a water-soluble coating is dissolved, a coated film is formed on the inner surface of the interior portion space **35a** included in the thermal insulation section **35**, which is provided in the accumulator container **25**, by sending electricity between an electrode and the accumulator container **25**. In the case of the electrodeposition coating, it is possible to easily drain, from the through hole, the water-soluble coating, entering from the through hole into the interior portion space **35a**.

Effects of Embodiment

As described above, in the rotary compressor **1** according to the embodiment, the accumulator container **25** is bonded to the compressor main body container **10**, and the partition member **28**, which partitions the interior portion, is provided in the interior portion of the accumulator shell **26**. The thermal insulation section **35**, which includes the interior portion space **35a** having a hollow structure that blocks a heat transfer from the compressor main body container **10** to the accumulator container **25**, is provided between the partition member **28** and the bottom shell **10c** that is included in the compressor main body container **10**. As a result of this, it is possible to enhance the thermal insulation property between the accumulator container **25**, which is bonded to the compressor main body container **10**, and the compressor main body container **10**. Therefore, even in the case of the structure in which the opening side **26a** of the accumulator shell **26** is bonded to the compressor main body container **10**, it is possible to suppress the heat, which is generated in the interior portion of the compressor main body container **10**, from being conducted to the accumulator container **25** by the thermal insulation section **35**, and it is thus possible to suppress the refrigerant, which is contained

in the accumulator container 25, from being heated. Therefore, it is possible to prevent a decrease in the efficiency of the rotary compressor 1 due to an occurrence of a pressure loss produced in accordance with a temperature rise of the refrigerant, which is sucked from the accumulator container 25 to the compressor main body container 10.

Furthermore, the rotary compressor 1 according to the embodiment, the bottom shell 10c, provided in the compressor main body container 10, is arranged by being inserted into the opening side 26a of the accumulator shell 26, and the opening side 26a of the accumulator shell 26 is bonded to the bottom shell 10c, provided in the compressor main body container 10. As a result of this, it is possible to easily apply the bottom shell 10c, which is provided in the compressor main body container 10, by using the existing compressor main body container 10, and inserting the bottom shell 10c into the opening side 26a of the accumulator shell 26, and also, it is possible to suppress an increase in the manufacturing cost by eliminating an attachment member, such as an attachment band, that is used to attach the accumulator container 25 to the compressor main body container 10. Furthermore, it is possible to avoid noise and vibration caused by the natural vibration frequency of another member as compared to the structure, in which the accumulator container 25 is indirectly coupled to the bottom shell 10c, provided in the compressor main body container 10, by way of the other member.

Furthermore, in the rotary compressor 1 according to the embodiment, the circumference wall 28a of the partition member 28 is bonded to the inner circumferential surface of the accumulator shell 26. As a result of this, it is possible to easily form, in a simple structure, the thermal insulation section 35, which includes the interior portion space 35a having a hollow structure in the interior portion of the accumulator shell 26, by the partition member 28.

Furthermore, as described above, in the accumulator shell 26, a through hole, which connects the interior portion space 35a that is provided in the thermal insulation section 35 and the outer side of the accumulator shell 26, may be provided. In this case, coating is applied on the inner surface of the thermal insulation section 35. As a result of this, it is possible to take outside air, surrounding the accumulator shell 26, into the interior portion space 35a by way of the through hole, and it is thus possible to drain the air, contained in the interior portion space 35a, by way of the through hole. As a result of this, even when the air, which is contained in the interior portion space 35a included in the thermal insulation section 35, is heated by heat transferred from the compressor main body container 10 to the thermal insulation section 35, the interior portion space 35a, included in the thermal insulation section 35, is ventilated by way of the through hole, so that it is possible to suppress a decrease in the thermal insulation property exhibited by the thermal insulation section 35. Therefore, it is possible to appropriately maintain the thermal insulation property exhibited by the thermal insulation section 35.

In the present disclosure, the structure of the opening side 26a of the accumulator shell 26 is not limited to the structure, in which the opening side 26a is bonded to the bottom shell 10c that is provided in the compressor main body container 10. Although not illustrated, the opening side 26a of the accumulator shell 26 may be bonded to the main shell 10a that is provided in the compressor main body container 10. Furthermore, the circumference wall 28a of the partition member 28, which forms the thermal insulation section 35, may be bent toward a lower part of the accumulator shell 26, and bonded to the inner surface of the

5 accumulator shell 26. Furthermore, although not illustrated, the accumulator shell 26 may include a main shell, which has a cylindrical shape and which includes an upper end portion corresponding to the opening side 26a, and a bottom shell, which has a cone shape and which is bonded so as to block the opening of the lower end portion of the main shell, and may be constituted such that, similarly to the compressor main body container 10, the bottom shell is bonded to the main shell. Furthermore, in the case where the through hole 10 is provided in the accumulator shell 26, by arranging the through hole at the upper part of the interior portion space 35a included in the thermal insulation section 35, and, by applying the coating in a state in which the vertical direction of the compressor main body container 10 and the accumulator container 25 is disposed in the opposite direction at the time of a process of manufacturing the rotary compressor 1, it is possible to easily drain, from the through hole, the water-soluble coating that has entered from the through hole into the interior portion space 35a.

15 20 In the following, a first and a second modifications will be described with reference to the drawings. In the first and the second modifications, components, having the same configuration as those described in the embodiment, are assigned the same reference numerals as those assigned in the embodiment, and descriptions thereof will be omitted.

First Modification

The first modification is different from the embodiment in 30 that the structure, including the third weld portion X and the fourth weld portion Y, in which the accumulator container 25 and the compressor main body container 10 are bonded, is used. FIG. 4 is an enlarged longitudinal sectional view of a relevant part according to the first modification.

35 40 As illustrated in FIG. 4, the partition member 28 according to the first modification is formed in a cup shape, and includes the circumference wall 28a that has a cylindrical shape. The lower part of the circumference wall 28a of the partition member 28 is bent with a curvature parallel to the inner circumferential surface of the opening side 26a of the accumulator shell 26, and is press fitted in the opening side 26a of the accumulator shell 26. Similarly, an opening side 28b of the circumference wall 28a of the partition member 28 is bent with a curvature parallel to the circumference wall 45 of the bottom shell 10c, provided in the compressor main body container 10, and the bottom shell 10c, provided in the compressor main body container 10, is press fitted in the opening side 28b of the circumference wall 28a of the partition member 28.

50 55 Then, in the first modification, the third weld portion X is formed, by bonding the inner circumferential surface of the circumference wall 28a of the partition member 28, to the outer circumference surface of the circumference wall of the bottom shell 10c of the compressor main body container 10. The fourth weld portion Y is formed, by bonding the inner circumferential surface of the opening side 26a of the accumulator shell 26, to the outer circumference surface of the circumference wall 28a of the partition member 28.

60 65 In also the first modification, similarly to the embodiment, in the thermal insulation section 35 provided in the accumulator container 25, there is no need to hermetically seal the interior portion space 35a by the third weld portion X, which is disposed between the circumference wall 28a of the partition member 28 and the bottom shell 10c provided in the compressor main body container 10, need not be continuously formed in the circumferential direction of the bottom shell 10c. Furthermore,

11

since the third weld portion X, which is disposed between the partition member 28 and the bottom shell 10c, is not continuously formed in the circumferential direction of the bottom shell 10c, an air gap, corresponding a portion in which the third weld portion X is not formed, also functions as an insulation space, so that it is possible to further suppress heat from being conducted from the compressor main body container 10 to the accumulator container 25.

According to the first modification, the lower part of the circumference wall 28a of the partition member 28 is able to be press fitted in the opening side 26a of the accumulator shell 26, and also, the bottom shell 10c of the compressor main body container 10 is able to be press fitted in the opening side 28b of the circumference wall 28a of the partition member 28, so that it is possible to weld the compressor main body container 10, the partition member 28, and the accumulator shell 26, while securing these components each other by a pressure. As a result of this, it is possible to enhance the manufacturability of the rotary compressor 1. In addition, in also the first modification, similarly to the embodiment, it is possible to enhance the thermal insulation property between the accumulator container 25 and the compressor main body container 10 by the thermal insulation section 35. Therefore, it is possible to suppress a refrigerant, which is contained in the accumulator container 25, from being heated by heat, which is generated in the interior portion of the compressor main body container 10, and it is thus possible to prevent a decrease in the compression efficiency of the rotary compressor 1.

As in the first modification described above, in the structure in which the opening side 26a of the accumulator shell 26 is bonded to the compressor main body container 10 disclosed in the present disclosure, the structure, in which the opening side 26a of the accumulator shell 26 is indirectly bonded to the bottom shell 10c of the compressor main body container 10 by way of the partition member 28, is included.

Second Modification

The second modification is different from the first modification in that a through hole 37, which passes through the interior portion space 35a included in the thermal insulation section 35, is provided in the partition member 28. FIG. 5 is an enlargement longitudinal sectional view of a relevant part according to the second modification.

As illustrated in FIG. 5, in the partition member 28 according to the second modification, the through hole 37, which passes through the interior portion space 35a of the thermal insulation section 35, is provided in the circumference wall 28a. Coating for preventing rust, being formed caused by dew condensation occurring in the interior portion space 35a, is applied on the inner surface of the interior portion space 35a provided in the partition member 28. The through hole 37 provided in the partition member 28 according to the second modification is formed above the fourth weld portion Y, and below a bent portion having a curvature parallel to the circumference wall of the bottom shell 10c of the compressor main body container 10. By forming the through hole 37 at such a position, it is possible to prevent the path, which connects the interior portion space 35a of the thermal insulation section 35 and the outer side of the accumulator shell 26 by way of the through hole 37, from being hindered by the opening side 26a of the accumulator shell 26 and the bottom shell 10c provided in the compressor main body container 10. As a result of this, it is possible smoothly fill the coating into the interior portion space 35a

12

by way of the through hole 37 when, for example, the coating is applied on the inner surface of the interior portion space 35a.

On the circumference wall 28a of the partition member 28, for example, a single piece of the through hole 37 having a slit shape, is provided, but the opening shape and the number of through holes 37 are not limited. For example, on the circumference wall 28a of the partition member 28, each of the plurality of through holes 37 may preferably be arranged at a position opposite to each other with the interior portion space 35a included in the thermal insulation section 35 between the through holes 37, which makes it possible to smoothly ventilate the air contained in the interior portion space 35a by way of the plurality of through holes 37.

Third Modification

FIG. 6 is an enlarged perspective view illustrating a relevant part according to the third modification. Regarding the third weld portion X disposed on the opening side 26a of the accumulator shell 26 described above in the embodiment, by forming a notch portion 39 as the through hole 37 at a part of the opening side 26a of the accumulator shell 26 in the circumferential direction, it is possible to obtain the same effect as that of the through hole 37 described above.

As illustrated in FIG. 6, in the third modification, the notch portion 39 is formed in a part of the circumferential direction of the end portion of the opening side 26a of the accumulator shell 26. The opening side 26a of the accumulator shell 26 is bonded, by the third weld portion X, along the circumferential direction of the opening side 26a except for the notch portion 39. As a result of this, it is possible to take outside air, surrounding the accumulator shell 26, into the interior portion space 35a included in the thermal insulation section 35 by way of the notch portion 39, and it is thus possible to drain the air, contained in the interior portion space 35a, from the through hole 37. Accordingly, even when the space inside the interior portion space 35a is heated by heat, transferred from the compressor main body container 10, it is possible to exhaust heat from the inner side of the interior portion space 35a to the outer side of the accumulator shell 26, so that it is possible to suppress a decrease in the thermal insulation property exhibited by the thermal insulation section 35.

In addition, the rotary compressor according to the present embodiment is not limited to a rotary compressor having a single cylinder, i.e., what is called a single-cylinder-type rotary compressor, but may be applied to a rotary compressor having two cylinders, i.e., what is called a two-cylinder-type rotary compressor. Moreover, the present embodiment has been described by using the rotary compressor as one example; however, for example, the present embodiment may be applied to a compressor, such as a scroll compressor, using another compression method, and it is possible to obtain the same effect as that described in the present embodiment.

REFERENCE SIGNS LIST

- 1 rotary compressor
- 10 compressor main body container
- 10c bottom shell
- 11 motor
- 12 compression section
- 25 accumulator container
- 26 accumulator shell
- 26a opening side

- 28 partition member
- 28a circumference wall
- 28b opening side
- 35 thermal insulation section
- 35a interior portion space
- 37 through hole
- 39 notch portion
- 104 suction pipe
- 107 discharge pipe
- V first weld portion
- W second weld portion
- X third weld portion (weld portion)
- Y fourth weld portion

The invention claimed is:

1. A hermetic compressor comprising:
  - a compressor main body container that is a vertical type having a cylindrical shape, and that is provided with a discharge pipe and a suction pipe for a refrigerant; an accumulator container that is connected to the suction pipe;
  - a compression section that is arranged inside the compressor main body container, that compresses the refrigerant, which has been sucked from the accumulator container by way of the suction pipe, and that discharges the compressed refrigerant from the discharge pipe; and
  - a motor that is arranged inside the compressor main body container, and that drives the compression section, wherein
  - the accumulator container includes an accumulator shell having a cup shape, and in which an opening side of the accumulator shell is bonded to the compressor main body container,
  - the accumulator shell has an interior portion including a partition member, which is formed in a cup shape and which partitions the interior portion,
  - the partition member has a circumference wall with a lower part bonded to the opening side of the accumulator shell, and has an opening side bonded to the compressor main body container, and
  - a thermal insulation section, which includes an interior portion space having a hollow structure that blocks a heat transfer from the compressor main body container to the accumulator container, is formed between the partition member and a bottom shell that is included in the compressor main body container.
2. The hermetic type compressor according to claim 1, wherein the circumference wall of the partition member is

provided with a through hole, which connects the interior portion space and an outer side of the partition member.

3. A hermetic compressor comprising:
  - a compressor main body container that is a vertical type having a cylindrical shape, and that is provided with a discharge pipe and a suction pipe for a refrigerant; an accumulator container that is connected to the suction pipe;
  - a compression section that is arranged inside the compressor main body container, that compresses the refrigerant, which has been sucked from the accumulator container by way of the suction pipe, and that discharges the compressed refrigerant from the discharge pipe; and
  - a motor that is arranged inside the compressor main body container, and that drives the compression section, wherein
  - the accumulator container includes an accumulator shell having a cup shape, and in which an opening side of the accumulator shell is bonded to the compressor main body container,
  - the accumulator shell has an interior portion including: a partition member which partitions the interior portion; and
  - a thermal insulation section, which includes an interior portion space being composed of only a hollow structure that blocks a heat transfer from the compressor main body container to the accumulator container, and is formed between the partition member and a bottom shell that is included in the compressor main body container,
  - the accumulator shell is provided with a through hole, which connects the interior portion space and an outer side of the accumulator shell,
  - the through hole is a notch portion that is formed in a part of a circumferential direction of an end portion of the opening side of the accumulator shell,
  - the accumulator container includes a weld portion, in which the opening side of the accumulator shell is bonded to the compressor main body container, and the weld portion is provided along the circumferential direction of the opening side except for the notch portion.
4. The hermetic compressor according to claim 3, wherein an outer circumference portion of the partition member is bonded to an inner circumferential surface of the accumulator shell.
